H. G. BUTT

PIPE WRENCH

Filed Sept. 16, 1925

Patented Sept. 6, 1927.

1,641,153

UNITED STATES PATENT OFFICE.

HERBERT G. BUTT, OF WINTHROP, MASSACHUSETTS.

PIPE WRENCH.

Application filed September 16, 1925. Serial No. 56,629.

One object of this invention is to provide a pipe wrench, the jaws of which are smooth and not liable to mar a pipe and are adapted to be quickly opened and closed, and, when 5 opened, are separated by a space which is wider than the diameter of a pipe to be engaged by the jaws, so that the jaws may be conveniently applied to a pipe located in a partially obstructed position, by an edge- 10 wise movement of the wrench in a direction at right angles to the axis of the pipe.

Another object is to enable the wrench to be conveniently adjusted to conform to pipes of different diameters.

15 Another object is to provide means preventing injurious or breaking strain on a lever portion of the wrench when the jaws are closed on a pipe.

Of the accompanying drawings forming a 20 part of this specification,—

Figure 1 is a side view of a pipe wrench embodying the chief features of the invention.

Figure 2 is an edge view of the same.

25 Figure 3 is a section on line 3—3 of Figure 1.

Figure 4 is a section on line 4—4 of Figure 1.

Figure 5 is a section on line 5—5 of Figure 1.

Figure 6 is a view similar to Figure 1, showing a different embodiment of the means for adjusting the swinging-jaw to vary its closing movement.

35 Figure 7 shows in longitudinal section the structure shown by Figure 6.

Figure 8 is a side view, showing the wrench provided with means for preventing breaking strain on a lever portion thereof.

40 Figure 9 shows in longitudinal section the structure shown by Figure 8.

Figure 10 is a section on line 10—10 of Figure 8.

45 Figure 11 shows in perspective, the swinging member of the coupling shown by Figures 8 and 9.

Figure 12 shows in perspective the pivot stud connecting the swinging and fixed members of the coupling.

50 The same reference characters indicate the same parts in all of the figures.

My improved pipe wrench comprises two 55 intersecting two-armed levers and a fulcrum stud pivotally connecting the levers at their

intersection, so that each lever includes an inner handle arm, projecting rearward from the fulcrum stud, and an outer arm projecting forward from the stud.

In the embodiment shown by Figures 1 to 60 5, inclusive, the fulcrum stud constitutes an element of means for varying the gripping movement or projection of the swinging-jaw hereinafter described, and thus enabling the wrench to conform to pipes of different 65 diameters, said stud including two aligned portions 12, 12, and eccentric portion 13, between the portions 12, and a head 14 at one end of the stud, adapted to be manually turned to vary the radial position of the 70 eccentric.

One of the levers includes an inner handle arm 15, and an outer arm 16, the inner edge of which is recessed, as shown by Figures 1, 6, 7, 8 and 9. A pipe-gripping jaw is fixed 75 to the outer arm 16 and preferably includes an extension 17, integral with the arm 16, and a facing member 18, having a substantially semi-circular gripping face, formed to conform to substantially one-half of the periphery of a zone of the pipe, the member 18 being detachably secured to the extension 17.

The other lever includes an inner handle 80 arm 19 and an arm 20, which is shorter than the arm 16, and constitutes a toggle arm or member.

The fulcrum stud connects the two levers at the point where they intersect, the outer arm 16 projecting farther from the stud 90 than the outer arm 20.

A swinging-jaw is pivoted by a pivot stud 21 to the outer arm 16, and is adapted to swing toward and from the jaw fixed to said arm. The swinging-jaw includes a body member 22, engaged with the pivot stud 21, and a substantially semi-circular gripping face formed on a facing member 23, detachably secured to the body member and formed to engage the opposite half of the pipe zone.

The swinging-jaw is connected with the shorter outer arm 20, by a link 25, connected by a pivot stud 26 with the arm 20, and by a pivot stud 27 with the swinging-jaw. The link 25 and the shorter arm 20 constitute a toggle, the arrangement being such that when the handle arms 15 and 19 are closed, as shown by full lines in Figure 1, the toggle is rendered active and projects the swinging- 110

jaw to its gripping position, and when the handle arms are opened, the toggle is broken and swings the swinging-jaw inward, as shown by dotted lines, the amplitude of the inward movement being such that the jaws are separated by a space of greater width than the diameter of a pipe which the jaws are adapted to engage. The wrench may, therefore be conveniently moved in a direction at right angles to a fixed pipe when the swinging-jaw is retracted, to locate the jaws in position to grasp the pipe.

The longer outer arm 16 is preferably curved or arched, and the fixed jaw faces inward, so that its inner side and the fixed jaw form a recess in which the swinging-jaw and the toggle are movable, the arrangement being such that when the swinging-jaw is relocated, the major portions of said jaw and the toggle are contained in said recess, the reentrant form of the recess permitting a maximum retraction of the swinging jaw and a pipe-receiving separation of its semi-circular gripping faces. The handle arm 15 is preferably U-shaped in cross section, and the handle arm 19 is preferably I-shaped in cross section, and adapted to enter the channel formed by the arm 15, as shown by Figure 3.

In the embodiment shown by Figures 1, 2 and 5, the eccentric 13 on the fulcrum stud may be partly rotated to vary its radial position and correspondingly vary the extreme of the forward extreme of the swinging-jaw.

In the embodiments shown by Figures 6, 7, 8 and 9, the fulcrum stud designated by 12^a is non-adjustable, and the toggle-link connecting the shorter arm 20 with the swinging-jaw is adjustable in length to vary the extreme of the forward movement of the swinging-jaw. Said link is composed of two externally threaded end members 30, one having a right hand and the other a left hand thread, a sleeve 31 having a right hand and a left hand internal thread, the members 30 and 31 constituting a turn-buckle. Rotation of the sleeve shortens or lengthens the link.

When the arm 16 and the fixed jaw form a relatively shallow recess, as shown by Figures 1, 6 and 7, the relative positions of the studs 12^a, 26 and 27, are such, when the swinging-jaw is retracted, that the toggle is movable from its inactive to its active position, by a movement imparted by the operator to the handle-arm 19, in the direction of the arrow α (Figure 6), but when the arm 16 and the fixed jaw form a deeper recess, as shown by Figures 8 and 9, which is sometimes preferable, the relative positions of the studs 12^a, 26 and 27, are such when the swinging-jaw is retracted, as shown by dotted lines in Figure 8, that the toggle cannot be moved to its active posi-

tion by a movement of the handle lever 19, by the operator, indicated by the arrow α , such movement tending to still further break the toggle. I therefore provide a biasing spring 33, one end of which is fixed at 34 to the arm 16, the other end being free and bearing on a portion of the toggle link. As shown by dotted lines in Figure 8, the spring is tensioned by a breaking movement of the toggle and exerts pressure on the toggle, forcing the handle arm toward the full line position, when it is released by the operator, until the relative positions of the studs are such that the operator is enabled to swing the handle arm 19 further in the same direction, and thus render the toggle active and project the swinging jaw.

It will be seen from the foregoing that the spring 33 is not required with the arrangement shown by Figures 1, 6 and 7.

To prevent the possibility of breaking the longer arm 16 by strain thereon, when the jaws are closed on a pipe, and particularly when the fixed jaw joins said arm, I provide coupling means bridging the recess formed by the longer arm and the fixed jaw, and adapted to prevent injurious flexure of said arm and jaw, when the swinging-jaw is projected.

Said coupling includes an inner member partly bridging the recess and preferably composed of a pair of spaced apart arms 36, one of which is shown by Figure 8, and the other by Figure 9, and a pivot stud 37, journaled in bearings in the outer ends of said arms, the arms being preferably cast integral with the handle arm 15. The coupling also includes an outer member, adapted to complete the bridging of the recess and preferably formed as a yoke including arm portions 38 (Figure 10) having orifices 39 in their inner ends, and a neck portion or abutment 40, connecting the outer ends of the arms.

The orifices 39 are semi-circular, and the stud 37 has semi-circular end portions 41, fitting the orifices. In assembling the parts, the stud 37 is inserted in its bearings in the arms 36, the end portions 41 projecting from the outer sides of the arms 36. The arms 38 of the outer coupling member or yoke are flexible and are sprung on to the projecting end portions 41, which are then upset at their outer ends against the outer sides of the arms 38, so that the stud is rigidly connected with said arms. The outer coupling member or yoke is thus adapted to swing to the position shown by Figure 9, and by full lines in Figure 8, until its neck portion or abutment 40 engages an undercut shoulder or abutment 42 on the fixed jaw, so that the coupling supports strain tending to injuriously flex the arm 16 and the fixed jaw. The outer coupling member is also adapted to be swung to the

dotted line position shown by Figure 8, so that it does not obstruct the jaws.

To yieldingly confine the outer coupling member in each of the positions shown, I cut away the stud 37, to provide a recessed flat face 44 (Figure 12) thereon, and secure to the handle arm 15 at 45, one end of a spring 46, the other end of which bears on the face 44, as shown by Figure 9, when 10 the outer coupling member is in its operative position. The spring coacts with the face 44 to snap the abutment 40 of the outer member into engagement with the abutment 42. When the outer coupling 15 member is turned back to the dotted line position (Figure 8), the spring has a sufficient frictional engagement with the rounded side of the stud 37, opposite the face 44, to prevent loose swinging movement of the 20 coupling member from the dotted line position.

It will be seen that the longer arm 16, and its extension 17, is recessed at its inner edge, and that the substantially semi-circular 25 smooth gripping face on the member 18 is within said recessed edge, and that the swinging jaw 22, pivoted to the recessed arm and provided with a substantially semi-circular smooth gripping face, formed on the 30 member 23, projects from the recessed edge and is adapted by the reentrant form of said edge, to be retracted, as indicated by dotted lines in Figures 1 and 8, sufficiently to enable the jaws, when fully opened, to be applied to a pipe by an edgewise movement of 35 the wrench, the gripping faces of the jaws having a pipe-receiving separation.

It will also be seen that when the jaws are in closed relation, the two smooth gripping faces conform closely to opposite sides of the periphery of a pipe and bear on practically all portions of a zone of said periphery, so that the jaws are adapted to exert sufficient turning force on the pipe, without 45 having toothed gripping faces liable to mar the pipe.

I claim:

1. A pipe-wrench comprising a pair of crossed levers connected by a fulcrum stud, 50 so that each lever has an elongated inner handle arm and a shorter outer arm, the outer arm of one lever being recessed at its inner edge and extended to form a fixed jaw having a substantially semi-circular smooth 55 gripping face within the recessed edge, the outer arm of the other lever being a toggle arm, which is shorter than the recessed arm, a swinging jaw pivoted to the recessed arm and projecting from the recessed edge there- 60 of, and having a substantially semi-circular smooth gripping face arranged to coincide

with the gripping face of the fixed jaw, so that the two gripping faces are adapted to substantially surround a pipe when the jaws are in closed relation, the recessed edge of 65 the outer arm permitting a sufficient retraction of the swinging jaw to enable the jaws to be applied to a pipe by an edgewise movement of the wrench, when the jaws are fully separated, and a link pivoted to the said 70 toggle-arm and to the swinging jaw, the toggle-arm and link constituting a toggle adapted to be rendered active by a closing movement of the handle arms, to close the semi-circular jaw faces on a pipe, and to 75 be broken by an opening movement of the handle arms, to cause the retraction of the swinging jaw into the recessed edge, and a pipe-receiving separation of said jaw faces.

2. A pipe wrench as specified by claim 1, 80 the link being constructed as a turn-buckle, adapted to be shortened and lengthened to vary the amplitude of the closing and opening movements of the swinging jaw.

3. A pipe wrench as specified by claim 1, 85 the wrench comprising also a coupling bridging the recess in the longer outer arm and adapted to prevent injurious flexure of the longer arm when the swinging-jaw is projected, said coupling including an inner 90 member fixed to the lever having the longer arm and partly bridging the recess, and an outer member pivoted to the inner member and adapted to complete the bridging of the recess, the longer arm and the free end of 95 the outer member being provided with complementary abutments, adapted to be pressed together by strain tending to flex the longer arm.

4. A pipe wrench as specified by claim 1, 100 the wrench comprising also a coupling bridging the recess in the longer outer arm, and adapted to prevent injurious flexure of the longer arm when the swinging-jaw is projected, said coupling including an inner 105 member fixed to the lever having the longer arm and partly bridging the recess, and an outer member pivoted to the inner member and adapted to complete the bridging of the recess, the longer arm and the free end of 110 the outer member being provided with complementary abutments, adapted to be pressed together by strain tending to flex the longer arm, means being provided for releasably 115 confining the outer member in an operative position, bridging the recess, and in an inoperative position, exposing a portion of the recess and permitting access to the jaws.

In testimony whereof I have affixed my signature.

HERBERT G. BUTT.
